UNITED STATES PATENT OFFICE.

MORRIS P. BRAY, OF ANSONIA, ASSIGNOR TO WARNER BROS., OF BRIDGEPORT, CONNECTICUT.

DESIGN FOR THE ORNAMENTATION OF CORSETS.

SPECIFICATION forming part of Design No. 18,840, dated January 8, 1889.

Application filed October 29, 1888. Serial No. 289,471. Term of patent 14 years.

To all whom it may concern:

Be it known that I, MORRIS P. BRAY, of Ansonia, in the county of New Haven and State of Connecticut, have invented a new Design for a Corset; and I do hereby declare the following, when taken in connection with accompanying drawing and the letters of reference marked thereon, to be a full, clear, and exact description of the same, and which said drawing constitutes part of this specification, and represents a face view of one-half the corset.

This invention relates to a design for a corset, having for its object the ornamentation of the exterior surface of the corset.

The exterior surface of the corset is represented as ornamented by a series of vertical stripes extending from top to bottom, leaving plain spaces between the stripes, each stripe representing several ribs, and the surface of the ribs ornamented. The ornamentation of the stripes, which extends throughout their length, is shown in full only near the ends, it being understood, however, that the ornamentation is continued throughout the stripes. In addition to the ornamented vertical stripes is the representation of two transverse stripes,

A B, the one stripe, A, represented as running from the front to rear above the waist-line and curved downward, the other stripe, B, represented as extending from front to rear below the waist-line, but curved upward, the two stripes A B represented as passing inside the vertical stripes, and the surface of the said stripes A B ornamented, all as shown in the accompanying illustration.

I claim—

The design for a corset, consisting in the ornamentation of the exterior surface by the representation of several vertical stripes, leaving plain spaces between them, the stripes representing vertical ribs and the surface of the ribs ornamented, combined with two stripes, A B, represented as extending from front to rear of the corset and appearing to pass inside the vertical stripes, the one stripe, A, curved downward and the other stripe, B, curved in the opposite direction, and the surface of said stripes A B ornamented, all as shown in the accompanying illustration.

MORRIS P. BRAY.
